1 Claim, 1 Drawing Sheet

Primary Examiner—Alan P. Douglas
Assistant Examiner—Clare E. Heflin
(74) Attorney, Agent, or Firm—Stetina Brunda Garred & Brucker

(57) CLAIM

The ornamental design for a concrete dowel tube with clip, as shown and described.

DESCRIPTION

FIG. 1 is a front bottom perspective view of the concrete dowel tube with clip of the present invention showing our new design; and,
 FIG. 2 is an end view thereof.
